(57) **CLAIM**

The ornamental design for a live video broadcasting device, as shown and described.

DESCRIPTION

FIG. 1 is a front, right, and top perspective view of a live video broadcasting device, showing my new design;

FIG. 2 is a rear, right, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is the enlarged view of the delineated region in FIG. 1; and,

FIG. 10 is the enlarged view of the delineated region in FIG. 5.

The dot-dash broken lines in FIGS. 1, 5, 9 and 10 form no part of the claimed design and delineate portions of the claimed design that are shown on an enlarged scale in FIGS. 9 and 10.

1 Claim, 10 Drawing Sheets
